ABSTRACT: In an ultrasonic welding tool of the kind comprising a relatively fixed frame, which supports an assembly including a transducer for converting electrical energy into ultrasonic vibrations, and a velocity transformer carried by the transducer for altering the amplitude of the vibrations produced by the transducer, the assembly is supported against lateral movement relative to the frame, by engaging an axially extending portion of the assembly, which is of substantially uniform cross section, as an axially sliding fit in a bearing, which is fixed relative to the frame in use, so as to support the assembly against lateral movement relative to the frame.

ULTRASONIC WELDING TOOLS

This invention is a continuation-in-part of my application Ser. No. 688,548, filed Dec. 6, 1967.

The invention relates to ultrasonic welding tools of the kind comprising a relatively fixed frame, an assembly including a transducer, secured to the frame by resilient means, for converting electrical energy into ultrasonic vibrations, and a velocity transformer carried by the transducer for altering the amplitude of the vibrations produced by the transducer, the velocity transformer being adapted to support a sonotrode shaped to engage a workpiece, and the assembly being supported against lateral movement relative to the frame.

In tools of the kind specified it has been the practice to support the assembly against lateral movement by clamping the transformer relative to the frame. However, since in use the transformer is subject to longitudinal vibrations it is necessary to attach the clamp to the transformer accurately at a position where a node occurs when the transformer vibrates.

Such arrangements are cumbersome and where it has been desired to produce a tool having a plurality of adjacent transducers and associated transformers and sonotrodes the proximity of the transducers and therefore of the sonotrodes has been governed by the spacing of the clamp arrangements.

According to the invention in a tool of the kind specified, the assembly is provided with an axially extending portion of substantially uniform cross section, said portion being received as an axially sliding fit in a bearing which is carried by said frame and which is fixed in use with respect to the frame, so as to support said assembly against lateral movement relative to the frame.

In the preferred example said axially extending portion is part of the velocity transformer. It is found that improved results are obtained if in this preferred embodiment, the transducer is also provided with an axially extending portion of substantially uniform cross section which is received as an axially sliding fit in a second bearing.

In the accompanying drawings FIG. 1 is a sectional view of an ultrasonic welding tool in accordance with one example of the invention, FIG. 2 is a view similar to FIG. 1 of a modification of the tool shown in FIG. 1, FIG. 3 is a perspective view of a compound arrangement of a plurality of the tools shown in FIG. 1, and FIG. 4 is a sectional side view illustrating another example of the invention.

Referring first to FIG. 1 of the drawings, there is provided a fixed frame 11 having secured thereto, by way of a resilient mounting 10, a transducer 12 for converting electrical energy into ultrasonic vibrational energy. The transducer 12 has engaged therewith a velocity transformer 13 for increasing the amplitude of the vibrations produced by the transducer. The transformer 13 includes a cylindrical shank 14 which is received as a sliding fit in a sleeve 15 secured to the frame 11. At its free end the shank 14 carries a sonotrode 16 which in use traps a workpiece against a relatively fixed anvil.

In use, as the tool operates the shank 14 is free to reciprocate axially within the sleeve 15 to transmit ultrasonic vibrations to the sonotrode 16, but is held against lateral movement which would result in lateral movement of the sonotrode relative to the workpiece.

Owing to the high frequency of the reciprocation of the shank, it is desirable, in order to avoid excessive heating of the sleeve 15, for the sleeve to be constructed in a material having low energy absorption properties, for example a material such as polytetrafluoroethylene. It will be appreciated that since the shank 14 slides in the sleeve 15 the positioning of the sleeve with respect to a vibrational node in the transformer is not critical. However, it is advantageous to position the sleeve 15 so that a vibrational node occurs in the transformer within the sleeve so that the sleeve and the shank are subject to the minimum relative movement.

In the modification shown in FIG. 2 the sleeve 15 is mounted in a spherical member 17 which is received in a corresponding spherical recess in the frame and through which the axis of the sleeve can be inclined with respect to the frame.

In addition, the transducer 12 is adjustably secured to the frame and so the working position of the sonotrode can be altered without the necessity of altering the position of the frame. The spherical recess in the frame 11 is defined in part by a locking ring 18 which can be tightened to lock the member 17 and consequently the sleeve 15 in the given position.

As the use of the sleeve 15 results in a compact assembly it will be appreciated that where a plurality of transducers with their respective sonotrodes are required adjacent one another, the proximity of sonotrodes is governed by the dimensions of the transformer and transducer, thereby permitting the sonotrodes to be positioned closer to each other than is possible with certain prior constructions. Such a compound arrangement is shown in FIG. 3 and comprises a plurality of transducers 12 with their respective transformers 13, sleeves 15 and sonotrodes 16, which are mounted in a common frame 11a.

Referring now to FIG. 4, there is provided a fixed frame 111 which at its upper end incorporates an inverted cup-shaped part 118 secured to the main portion of the frame and constituting part thereof. There is further provided a transducer 112 for converting electrical energy to ultrasonic vibrational energy, the transducer 112 having engaged therewith a velocity transformer 113 for increasing the amplitude of the vibrations produced by the transducer 112. The transformer 113 includes a cylindrical shank 114 which is received as a sliding fit in a sleeve 115 secured to the frame 111. At its free end the shank 114 carries a sonotrode 116 which in use traps a workpiece against a relatively fixed anvil.

The transducer 112 is also formed with an axially extending portion 109, the portion 109 being accommodated within the part 112 in sliding engagement with a cylindrical bearing 108. The upper end of the portion 109 is spaced from the base of the part 112 by resilient means 110, and the assembly 109, 112, 113, 114, 116 is locked against rotation by a pin 107 extending from the part 118 through the resilient mounting 110 into the portion 109, material 117 having low energy-absorbing properties being provided around the portion of the pin 107 within the portion 109. Preferably the length of the portion 109 is one-fourth wavelength.

In use, as the tool operates the shank 114 is free to reciprocate axially within the sleeve 115, and the portion 109 is free to reciprocate axially within the bearing 108. However, the assembly is held against lateral movement which would result in lateral movement of the sonotrode 116 relative to the workpiece. It is preferable, in view of the high frequency of the reciprocation of the shank, for the sleeve 115 and the bearing 108 to be constructed in a material having low energy absorption properties, for example polytetrafluoroethylene. The use of such a material avoids problems due to overheating, and it will be appreciated that by virtue of the arrangement described using the sleeve 115 and bearing 108, the positioning of the sleeve 115 and bearing 108 with respect to a vibrational node in the assembly is not critical. However, it is advantageous to position the sleeve 115 and bearing 108 so that vibrational nodes occur within the sleeve 115 and bearing 108, because in this way the sleeve 115 and bearing 108 are subject to minimum relative movement.

The example described is a modification of FIG. 1, but the other examples can be modified in a similar manner.

Means other than the pin 107 could be used to prevent rotation of the assembly 109, 112, 113, 114, 116. For example a fixed bar could be used, the bar having polytetrafluoroethylene studs which press against the sonotrode 116.

Having thus described my invention what I claim as new and desire to secure by Letters Patent is:

1. An ultrasonic welding tool comprising a relatively fixed frame, an assembly including a transducer for converting electrical energy into ultrasonic vibrations, resilient means mounting the transducer on the frame, a velocity transformer carried by the transducer, the velocity transformer altering the am-

plitude of vibrations produced by the transducer, and being arranged to support a sonotrode shaped to engage a work-piece, and a bearing arrangement supporting the assembly against lateral movement relative to the frame, the bearing arrangement including a first part constituted by an axially extending portion of the velocity transformer, said portion being of substantially uniform cross section, and being received as an axially sliding fit in a second part of the bearing, the second part being carried by the frame and being fixed in use with respect to the frame, so that the bearing supports the said assembly against lateral movement relative to the frame.

2. A tool as claimed in claim 1 wherein said second bearing part is constituted by a sleeve, formed in a material having low energy absorbing properties.

3. A tool as claimed in claim 1 wherein said second bearing

part is formed in polytetrafluoroethylene.

4. A tool as claimed in claim 1 wherein said assembly is adjustably mounted in said frame and said second bearing part is mounted in the frame in such a manner that the second bearing part can be moved so that its axis is tilted with respect to the frame.

5. A tool as claimed in claim 1 including a plurality of assemblies and bearings supported in a common frame.

6. An ultrasonic welding tool as claimed in claim 1 in which 10 the transducer is also formed with an axially extending portion of substantially uniform cross section, said portion of the transducer being received as an axially sliding fit in a second bearing which is carried by said frame and which is fixed in use with respect to the frame.
